UNITED STATES PATENT OFFICE.

RUSSELL V. APPLETON, OF PITTSBURGH, PENNSYLVANIA, ASSIGNOR OF FORTY AND ONE-HALF PER CENT TO ARCH WELTY, SIXTEEN AND ONE-HALF PER CENT TO ARTHUR WELTY, AND TWO AND ONE-HALF PER CENT TO FRED WELTY, ALL OF CHICAGO, ILLINOIS.

CENTRIFUGAL FREQUENCY-TIME-ELEMENT RELAY.

Application filed October 1, 1925. Serial No. 59,800.

My invention pertains to features of novelty, both structural and functional, in electrical relays and relates more especially to improvements in appliances of this character 5 which act with a time element or delay and which depends upon different centrifugal actions occasioned by various frequencies impressed on the device.

One object of the invention is to provide 10 a time element relay which has both slow and quick actions, or operations at substantially different speeds, which can be controlled by modifying the frequencies impressed on the circuit, these slow and quick operations being employed to make and break contacts at predetermined time elements for train-control purposes or analogous uses.

Another of the features of the invention is 20 the production of a relay that is self-locking according to the frequencies used in the circuit, the impressed frequencies locking the relay in a particular position until a new frequency is employed.

25 Another aim of the invention is to supply an apparatus of this character in which one contact is adapted to close its circuit slowly upon energization of the relay and to open it quickly upon de-energization, the other contact closing quickly upon such energization and opening slowly upon de-energization of the magnet.

The invention concerns more particularly 35 a construction based on the use of a centrifugal apparatus mounted on the rotor shaft of the relay which determines what contact is to be operated and that in turn is governed by the frequency impressed on the circuit.

An added aim or purpose of the invention 40 is to provide a device having the specified characteristics which is simple in construction, effective in use, and which can be provided at relatively small cost.

To enable those skilled in this art to have 45 a full and complete understanding of the invention, in the accompanying drawing, forming a part of this specification, and throughout the several views of which like reference characters have been used to designate the same parts, a present desirable and preferred embodiment of the invention has been illustrated more or less diagrammatically.

In this drawing:

Figure 1 is an illustration of an entire 55 apparatus, some of the details of the structure being omitted to more clearly present its more important parts;

Figure 2 is a diagram of the circuits for 60 the motor employed; and

Figure 3 is a horizontal section on line 3—3 of Figure 1.

Referring to this drawing, it will be seen that the new appliance includes an induction-motor 21 of known type, the wiring diagram 65 of which is shown in Figure 2, wherein the three leads 22, 23 and 24 are connected to the rotor 25 and the field 26 in the way clearly depicted.

The shaft 27 of such motor has a plurality 70 of arms 28 hinged thereon, each such arm at its lower or outer end having a weight or centrifugal ball 29, the members 28 being connected by a corresponding or other number of links 31 to a disk 32 on a reciprocating 75 shaft 33 revoluble in bearings, not shown, and equipped with an elongated gear 34 and at its upper end with a double or duplex bevel-gear 38.

Gear 34 is constantly in mesh with and 80 drives a gear element having teeth 35 on its side meshing with those of the gear 34 and teeth 36 on its edge in cooperative relation with those of a hinged or pivoted sector 37, whereby the motor by the gearing specified 85 actuates such sector so long as the latter is permitted to remain in mesh with its companion gear 36.

When the slidable shaft 33 is in a lower 90 position, as shown in Figure 1, the location of the shaft being dependent upon the speed of rotation of the rotor of the motor, which in turn is governed by the frequency of the electric current supplied thereto, gear 38 is in mesh with and revolves a bevel-gear 39 95 on a suitably-supported shaft 41 equipped with a collar or enlargement 42 fitted with a laterally-outstanding pin or lug 43 located beneath the lower end of an appropriately-guided bar or rod 44 pivotally connected at 100 45 to a contact lever 46 fulcrumed at 47 on a stationary support and at which point it is also connected to an electric conductor 48.

When the shaft 33 is in a more elevated 105 position, by reason of a greater speed of rotation of the rotor, because of a current of

greater frequency supplied thereto, the upper section of the duplex gear 38 meshes with another bevel-gear 49 on a revoluble shaft 51 having a collar or enlargement 52 equipped with an outstanding pin 53 below the lower end of, and adapted to coact with, a rod 54 hinged to the contact lever 46 at 55 on the opposite side of the fulcrum 47 from the connection 45.

10 The contact lever 46 and its associated parts as described are balanced as to their weight with respect to the fulcrum, so that the lever will remain in any position in which it may be placed until moved or 15 shifted therefrom.

Sector 37 is fulcrumed or hinged at 56 on the sliding armature 57 of an electro-magnet 58, a spring 59 normally pressing the sector into toothed engagement with its 20 related gear 36. The magnet, however, when energized being capable of over-powering the action of the spring and withdrawing the sector from cooperative relation with its gear.

25 The sector carries two, parallel, spring contacts 61 and 62 on an insulation-block 63, these contacts being adjacent to the lower free end of the contact arm or lever 46, the latter in one side having an insert 64 of insulating material.

30 Both of these contacts 61 and 62 are electrically connected by a wire 65 to one terminal of the magnet, the companion terminal being joined to a wire 66, the remainder of 35 the circuit between the latter and the conductor 46 not being shown because unnecessary for a full understanding of the present invention.

An arm 67 fulcrumed on a stationary support at 68 carries an insulated leaf-spring contact 69 connected to a conductor 71 and adapted to play or move between a back contact 72 in a "stop," "cut-in" or other circuit and a front contact 73 in a "proceed" or other 45 proper circuit.

50 Another arm 74 is freely oscillatory on the fulcrum pin or shaft 68 and carries an insulated leaf-spring contact 75 joined to a conductor 76 and adapted to move between two back contacts 77 and 78, the latter conveniently being in a "caution" "cut-in" circuit 55 controlled by the speed of the train and the former in any appropriate circuit, and a front contact 79 in a "caution" or other circuit.

55 A bar 81, loosely pivotally-connected at 82 to the arm or lever 67, has a pin and slot connection 83 with the segment and a similar pin and slot connection 84 with a short link 85 hinged at 86 to the switch-arm 74.

60 When the motor is operating at a low frequency, for example 25 cycles per second, the gear 38 will revolve shaft 41 and pin 48 through the means of gear 39 and the movement of the pin will raise rod 44 and give

the contact lever 46 a definite position which it will thereafter maintain, the continued idle revolution of the pin with the shaft having no subsequent effect on the part 46.

The revolution of shaft 33 through gears 70 34, 35 and 36 will rock the sector 37 and its contacts 61 and 62 upwardly toward the now stationary contact-arm 46.

As soon as the sector begins its movement carrying the bar 81 with it, the latter 75 through the link 85 will quickly rock arm 74 to move the contact 75 away from the switch terminals 77 and 78 and into contact with the front switch terminal 79, thus breaking the two circuits and making or 80 closing the one.

Before the travel of the sector can shift the switch contact 69, however, the contact 61 will have engaged the complementary contact 46 thereby closing the circuit through 85 the electro-magnet, the energization of which effects the withdrawal of the sector from cooperative action with its gear, hence terminating its turning movement, and the parts are held in this relation until the magnet is 90 de-energized, when the weight of the elements involved will restore the sector and the switch members to their original positions.

95 It is to be remembered that members 67 and 74 are separate elements independently fulcrumed at 68 and that arm 67 is actuated by bar 81 when the latter moves directly upwardly by reason of the connection at 82. Member 67 does not move until sector arm 100 81 moves upwardly because of the slot connection 83 and arm 74 moves only when sector bar 81 pulls link 85 in a vertical movement because of slot 84.

105 Thus it will be seen that when low frequency is impressed upon the relay circuits, the centrifugal apparatus revolves double-bevel gear 38 at the position shown in the drawing, meshing with gear 39, therefore pushing arm 44 upwardly by member 43 to 110 the position shown, so that finger 46 remains near contact 61. As the sector moves such contact upwardly, it immediately engages or presses against finger 46 thereby providing a circuit to magnet 58, pulling sector 115 gearing from the gear 36 and holding it in that position.

The first tendency of the sector arm 81 is to move toward the left pulling link 85 with it and by the time sector bar 81 will be so 120 moved actuating link 85, arm 74 and contact 75 so as to cause the latter to engage contact 79, the contact 61 would have engaged with finger 46.

125 In case the motor is operated at a higher frequency, and consequently at a greater speed, the gear 38 will be brought into mesh with gear 49 and the consequent rotation of pin or lug 53 through bar 54 will position the contact lever 46 at a higher location 130

or elevation so that a greater degree of turning of the sector will be required before contact is made with such member 46.

The sector will be rocked as before quickly moving switch contact 75 from contacts 77 and 78 and against contact 79, as in the previous instance, but before the magnet is supplied with current by the engagement of the contacts 61 and 46, the loose or pin and slot connection of the bar 81 with the sector will have been taken up or reached its limit so that continued turning of the sector lifts the bar sufficiently to rock switch lever 67 and move contact 69 from contact 72 over 75 against the front contact 73, thus bringing about the desired change in circuit connections.

As in the previous case, when the magnet is de-energized the parts fall to their original positions by reason of their weights.

When higher frequency is in the relay circuit, gear 49 is in mesh with the double-bevel gear 38 so that lug 53 moves the finger 46 to the right and upwardly sufficiently so 25 that when the sector rocks upwardly with its contacts 61 and 62, contact 61 would not touch finger 46 because of the position it would obtain when moved by the sector in a quarter circle, but contact 62 would press 30 directly against the finger 46 and close the magnet 58 circuit. It is to be understood that the insulation 64 on finger 46 is there as a safeguard, so that if the arms 44, 54 and 46 become bent, the energization of the magnet 35 would not be effected.

When such higher frequency is in the circuits of the relay, the sector continues to travel but brings slot 84 into play, so that the pin of arm 85 slides down in slot 84 as 40 sector arm 81 moves upwardly and takes up such upward play to prevent arm 74 from moving any further.

Contact 61 simply moves entirely out of line of contact with arm 46 raised higher 45 than on low frequency. This is controlled by lug 43 pushing arm 46 down further than lug 53 will do. If low frequency is operating the motor, lug 43 pushes arm 46 down to its lowest point toward contacts 61, 62 and as the sector moves upwardly contact 50 61 comes into contact with arm 46 first and completes the circuit to magnets 58. If the high frequency current is impressed on the motor, the centrifugal action will move gear 55 38 to gear 49 so that lug 53 pushes arm 46 upwardly away from contact 61 breaking the magnet 58 circuit and sector 37 will fall upon gear 36 and will be moved upwardly again. Since arm 46 is farther away from 60 its former position, contact 61 will pass beyond arm 46 entirely and as the sector moves in a quarter circle contact 62 below contact 61 will touch arm 46.

Thus it will be seen that when either frequency is used, switch member 75 is quickly

operated, but the delayed or retarded action of the switch-element 69 only occurs when a current of the greater or higher frequency is employed.

In case the appliance should be operating 70 under slow speed and low frequency and the contact 61 is near and approaching the depressed contact arm 46 and the frequency should be quickly changed to the higher one, the upward rocking of the sector would continue at increased speed and if the pin 53 did not quickly change the position of the member 46, spring 61 would become bent downwardly unduly and possibly injured.

Under these circumstances, spring 61 so 75 would pass up beyond the end of arm 46 and rest on the insulation insert 64 until the lower contact 62 engages the arm and energizes the magnet.

The double contact feature and the associated insulation insert constitute a safety measure under such circumstances.

The invention is not limited and restricted to this particular embodiment of the invention and many minor mechanical changes 90 may be incorporated in such a structure without departure from the heart and essence of the invention and without the sacrifice of any of its substantial benefits and 95 advantages.

I claim:

1. In an appliance of the character described, the combination of an electric-motor adapted to be operated at two different speeds by reason of currents of two different 100 frequencies supplied thereto, means carrying an electric-contact moved by said motor, another relatively-stationary adjustable contact with which said first contact is designed to engage, centrifugal means operated by 105 said motor controlling the position of said second contact, an electro-magnet in the circuit of said contacts which, when energized, breaks the operative connection between said motor and said first electric-contact.

2. In an appliance of the character described, the combination of an electric-motor subject to operation at different speeds by reason of electric currents of different frequencies supplied thereto, a sector geared to 110 and turned by said motor, an electro-magnet to break said gear connection when energized, an electric-switch in the circuit of said electro-magnet a movable contact of which is 115 operated by said sector, centrifugal means operated by said motor to determine the position of the companion contact of said switch, and another electric switch operated by said sector.

3. In an appliance of the character described, the combination of an electric-motor subject to operation at different speeds by reason of electric currents of different frequencies supplied thereto, an electro-magnet, 120 a switch in the circuit of said electro-magnet,

a driving connection between said motor and a movable contact of said switch, means whereby said electro-magnet when energized breaks said driving connection, centrifugal means operated by said motor determining the position of adjustment of the companion contact of said switch, and a second switch operated by said driving connection.

4. In an appliance of the character described, 10 the combination of an electric-motor subject to operation at different speeds by reason of electric currents of different frequencies supplied thereto, an oscillatory sector, a gear rotated by said motor to turn said sector, an electro-magnet adapted to withdraw said sector from operative engagement with said gear, an electric-switch in the circuit of said electro-magnet having a movable contact on said sector and a companion contact, centrifugal means driven by said motor to position said companion contact according to the speed of rotation of the motor, two other switches, a bar slidably mounted on said sector, and means connecting said bar to said two switches to operate them in sequence.

5. In an appliance of the character described, the combination of an electric-motor subject to operation at different speeds by reason of electric currents of different frequencies supplied thereto, an oscillatory sector, a gear rotated by said motor to turn said sector, an electro-magnet adapted to withdraw said sector from operative engagement with said gear, an electric-switch in the circuit of said electro-magnet having a movable contact on said sector and a companion contact, a slideable shaft, centrifugal means driven by said motor to rotate said shaft and slide it in accordance with the speed of the motor, a gear on said shaft, a pair of gears with either one of which said latter gear may mesh depending upon the speed of the motor, means connecting said pair of gears to said companion switch contact whereby the adjustment of the latter is determined by which gear is active thereon, a bar slidably

mounted on said sector, a second switch with which said bar is connected, a third switch, and a link pivoted thereto and having a pin and slot connection with said bar, whereby turning movement of the sector operates the third switch first and the second switch later provided the sector has not been disconnected from its gear in the meantime by the action of the electro-magnet.

6. In an appliance of the character described, the combination of an electric-motor subject to operation at different speeds by reason of electric currents of different frequencies supplied thereto, two electric-switches, and means including an electro-magnet connecting said motor to said switches to operate the latter, one of said switches closing quickly and opening after a period of de-energization of the magnet, the other switch closing after a period and opening quickly upon de-energization of the magnet.

7. In an appliance of the character described, the combination of an electric-motor adapted to be operated at different speeds, an electric-switch, means whereby said motor operates said switch, an electro-magnet acting on said means to break the connection between the motor and the switch and to maintain the latter in the position which it occupies when such connection is broken until the electro-magnet is de-energized.

8. In an appliance of the character described, the combination of an electric-motor adapted to be operated at different speeds, a pair of electric switches, means whereby said motor operates said switches in sequence, and an electro-magnet acting on said means to break the connection between the motor and the switches and to maintain the latter in the positions they occupy when such connection is broken until the electro-magnet is de-energized.

In witness whereof I have hereunto set my hand.

RUSSELL V. APPLETON.
